BUTTON LOOP

Application filed June 23, 1929. Serial No. 374,398.

This invention relates to button loops having expansible contracted throats through which the button receiving loop communicates with the button retaining loop.

5 The object of the invention is to provide a button loop with automatic means for rendering an expansible throat rigidly contracted as a safety means for positively retaining the button shank behind the throat.

10 The invention consists in the novel constructions, to be hereinafter described or claimed, for carrying out the above stated object and such other objects as may herein-after appear.

15 The character of the invention may be best understood by reference to one illustrative device embodying the invention and illustrated by the several figures in the accompanying drawing in which the Figure 1

20 is an elevation of a button loop with expansible throat portion; the Figure 2 is a similar elevation, but illustrating a rigidly locked throat portion; and the Figure 3 is a top view of the locking member.

25 The invention is not limited to any specific form of construction and the details of the device may be varied to produce the novel features hereinafter claimed, the device as illustrated, however, is a button loop

30 comprising the suspension loop 1, the button receiving loop 2, the contracted throat portion 3, the button retaining loop 4, and the locking member having the sliding bar 5 and integral therewith the button receiving loop

35 6. The button loop is preferably formed of a piece of resilient wire a middle portion of which is bent to form the button retaining loop 4 with the contracted throat portion 3, the remaining wire ends forming the slightly

40 convergent side arms 7 and 8 of the button receiving loop 2, and the wire extremities being looped, as at 9 and 10, in a plane perpendicular to the plane of the button loop.

45 The end suspension loop 1 is preferably made of wire bent therefor and to provide a lower bar 11 formed as an arc having its center at the base of the retaining loop 4, the wire ends abutting and being welded. The looped extremities 9 and 10 are mounted upon

50 the arc 11 for a pivotal and sliding move-

ment thereon. The locking member, as illustrated by the Figure 3, is preferably made of a piece of wire having its ends welded to provide an endless loop. The wire is then bent to form the sliding bar 5, looped around 55 the side arms 7 and 8, and the second button receiving loop 6 the base of which normally lies across the upper portion of the button retaining loop 4.

A button having been received within the 60 superimposed button receiving loops 2 and 6, the button shank 12 may rest upon the contracted throat 3, as illustrated by the Figure 1. It is obvious that, as the button

is urged downwardly, the shank will act as 65 a cam to operate and expand the throat 3 to pass therethrough, the arms 7 and 8 freely oscillating by reason of their looped extremities 9 and 10 describing an arc identical with that of the bar 11 along which they 70 must travel. The shank 12 having passed the throat 3 the resiliency of the wire returns the throat to its normal contracted condition, as is usual with such constructions,

but the sliding bar 5, by means of the engagement of the shank 12 with the base of the sliding member, is carried down the arms 7 and 8, relatively divergent as regards the sliding course of the looped bar 5, the arms 7 and 8 being thus made rigid against oscillation and hence the throat 3 being made

75 rigid, as illustrated by the Figure 2. To release the button from within the retaining loop 4, the bar 5 is manually lifted, the base of the locking member lifting with it the 80 shank 12 through the throat 3 which, by reason of the return of the bar 5, is again expandable.

I claim:

1. A button loop comprising associated 90 button receiving and retaining loops in axial alignment and formed by resilient side arms diverging downwardly to form the button receiving loop, and then bent inwardly to provide an expansible but normally contracted entrance to the retaining loop, and means mounted upon the side arms and movable only along the plane of the loop and adapted in one position to lock and maintain the contracted entrance rigid, said means being op- 95 100

erable by the shank of a button moving from the receiving loop into the retaining loop.

2. A button loop comprising associated button receiving and retaining loops in axial alignment and formed by resilient side arms diverging downwardly and forming the receiving loop and then bent inwardly to provide an expandible but normally contracted entrance to the retaining loop, and a locking member slidably mounted upon the side arms and having a base portion normally extending across the retaining loop and adapted to be carried by a button shank moving into the retaining loop to operate the sliding member to a binding position upon the side arms and hence to maintain the throat rigid against expansion.

3. A button loop having resilient side arms of which a portion diverges downwardly, the arms cooperating to provide associated loops in axial alignment, the loops having between them an opening comprising an expandible throat normally contracted, and means mounted upon the divergent portion of the side arms and movable only in the plane of the loop to opposite extreme positions of which one rigidly locks the contracted throat against expansion.
